US00D876389S

(12) **United States Design Patent** (10) Patent No.: **US D876,389 S**
Brunner et al. (45) Date of Patent: **** Feb. 25, 2020**

(54) **AUDIO LISTENING SYSTEM**

(71) Applicant: **Apple Inc.**, Cupertino, CA (US)

(72) Inventors: **Robert Brunner**, San Francisco, CA (US); **Gregoire Vandenbussche**, San Francisco, CA (US); **Christopher Fruhauf**, San Anselmo, CA (US)

(73) Assignee: **Apple Inc.**, Cupertino, CA (US)

(***) Term: **15 Years**

(21) Appl. No.: **29/668,071**

(22) Filed: **Oct. 26, 2018**

(56)

(57) **CLAIM**

The ornamental design for an audio listening system, as shown and described.

DESCRIPTION

FIG. 1 is a front perspective view of an audio listening system showing the claimed design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines in the figures show portions of the audio listening system that form no part of the claimed design.
